CLAIM

The ornamental design for a shank for a nut driver having a multiple sized socket at the handle end, as shown and described.

DESCRIPTION

FIG. 1 is a perspective view of my shank for a nut driver having a multiple sized socket at the handle end showing my new design;

FIG. 2 is a reverse perspective view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a top plan view thereof;

FIG. 8 is a bottom plan view thereof;

FIG. 9 is a perspective view thereof; and,

FIG. 10 is a reverse perspective view thereof.

The broken line showing of handle in FIG. 9 and FIG. 10 is included for the purpose of illustrating environmental structure and forms no part of the claimed design.

The irregular shaping shown at the bottom of the claimed design is a graphic form indicating no particular length. The claim is understood to be limited to that which is shown.
